UNITED STATES PATENT OFFICE.

CHESTER H. STEELE, OF QUAKER CITY, AND FRANK H. SCATTERGOOD, OF GEORGETOWN,
OHIO.

MOLDING-MACHINE.

1,256,729.

Specification of Letters Patent. Patented Feb. 19, 1918.

Application filed July 10, 1917. Serial No. 179,658.

To all whom it may concern:

Be it known that we, CHESTER H. STEELE and FRANK H. SCATTERGOOD, citizens of the United States, residing at Quaker City, 5 Guernsey county, Ohio, and Georgetown, Brown county, Ohio, respectively, have invented certain new and useful Improvements in Molding-Machines, of which the following is a specification.

10 This invention relates to molding machines and has more especial reference to an improved delivering pneumatic molding machine.

The invention has for its dominant object 15 to provide a molding machine designed to reduce the time of operation as well as the labor employed in the making of molds, the machine being adapted to receive a pattern and flask thereon and to thoroughly tamp 20 the molding sand therein in order that a perfect mold will be produced.

Another object of the invention is to provide the molding machine with an adjustable work receiving table for receiving the 25 flask and pattern from the same after the tamping of the molding sand therein.

It is also an object of the invention to 30 provide novel pneumatically operated means for moving the flask from the machine onto the work receiving table so that the mold can be readily removed therefrom.

Other independent objects are to provide 35 features of construction of portions of the machine which tend toward the attainment of the above aims irrespective of the relation in which they are used.

Other objects will be in part obvious and in part pointed out hereinafter.

The invention accordingly consists in the 40 features of construction, combination of elements and arrangement of parts which will be exemplified in the construction herein- after set forth, and the scope of the applica- 45 tion which will be indicated in the following claims.

In the accompanying drawings, wherein is shown one of various possible embodiments of our invention:

Figure 1 is a top plan of the improved 50 molding machine;

Fig. 2 is a front elevation thereof;

Fig. 3 is a rear elevation;

Fig. 4 is a longitudinal section through the machine;

Fig. 5 is a transverse section therethrough, 55 and

Fig. 6 is a fragmental detail in side elevation showing the pneumatic operated means for moving the machine work table.

Similar reference characters refer to similar parts throughout the several views of the drawings.

Having more particular reference to the drawings, 1 designates the base of the molding machine, feet 2 being formed upon the 65 lower portions thereof in order that the same may be efficiently secured to a suitable bed or other support. Carried by the base 1 and preferably substantially concentric thereof is a vertically disposed cylinder 3 70 having a fluid inlet port 4 formed in one side thereof, the said port being controlled by means of a spring balanced valve herein- after more fully described. Pockets are formed in the upper extremity of the base 1 75 and receive therein cushioned buffering blocks 4', these blocks serving as shock absorbing means for the molding machine subbase. To the inner side of the base 1 there is secured a plurality of guide brackets generally 80 indicated by the numeral 5.

Movable within the vertical cylinder 3 is a piston 6 carrying on its upper end a sub- base 7 having a plurality of circularly dis- 85 posed bosses 8 formed upon its under surface and adapted to engage the buffering blocks 4'. As will be noted, the subbase 7 is substan- tially square and is provided with a depend- ing marginal flange 7', the purpose of which will be subsequently apparent. To afford 90 a fluid tight engagement between the cylin- der 3 and the piston 6 a stuffing gland 9 may be and preferably is secured to the upper extremity of the said cylinder and has engagement with the sides of the pis- 95 ton 6.

Hinge elements 10 are secured to one side of the marginal flange 7' and receive there- through a shaft 11, while other hinge ele- 100 ments 12 carried upon a work table 13 are arranged upon the said shaft 11, coiled springs 14 being also arranged upon the shaft and engaged with the hinge elements 10 and 12 in order that the hinged work table 13 will be properly balanced, it be- 105 ing understood that one set of the coiled springs 14 are at all times in tension against the remaining set of springs. To prevent

the occurrence of suction between the sub-base 7 and the under side of the work table 13, the said under side of the work table is recessed as at 15, and obviously, tends to break the same, thus, allowing free movement of the hinged work table when it is desired.

Oppositely disposed vertical grooved keepers or guides 16 are arranged upon one side of the base 1 and receive therein complementally formed portions, preferably, the heads of bolts 17 which are in turn secured to the adjacent vertical portion of a work receiving table 18. By so engaging the work receiving table with the base 1 it will be appreciated that the same may be adjusted vertically. To effect such vertical adjustment of the table 18, a screw-threaded shaft 19 is loosely engaged therewith and received through a screw-threaded boxing 20 secured to a laterally offset portion formed upon the bottom of the base 1. A beveled gear 21 is carried upon the upper end of the screw-threaded shaft and is in mesh with a similar gear 22 keyed to the adjacent end of a shaft 23 journaled in bearing brackets 24 upon the under side of the work receiving table and having a squared extremity in order that a suitable turning implement may be engaged with the same. Upon the upper face of the work receiving table 18 is a transversely disposed web 25, while mounted rearwardly thereof and arranged in a suitable depression or seat 26 is a compensating beam 27, serving for an obvious purpose.

To cause pivotal movement of the work table 13 pinions 28 are keyed to the opposite ends of the shaft 11 and mesh with rack elements 29 formed upon the rear extremities of pistons 29', the heads of which work within cylinders 30 secured by bolts 31 or other suitable fastening devices to the opposite forward marginal portions of the sub-base 7. By this form of gearing, when reciprocatory motion is imparted to the racks 29 the pinions 28 will be rotated in a direction to cause pivotal movement of the work table 13, the hinge elements 12 of which are keyed to the shaft 11.

As means for supplying motive fluid to the cylinders 30 a supply conduit 32 is employed and has the passage of the motive fluid therethrough controlled by a three-way valve 33 having an operating handle 34 connected to the plug thereof. Branch conduits 35 extend from several of the ports of the valve 33 into engagement with the heads of the cylinders 30. Thus, by moving the plug of the valve 33 to open position through the medium of the handle 34 air or other suitable motive will be admitted to the cylinders 30, thereby causing reciprocatory movement of the pistons 29' and their respective rack portions 29.

A second supply conduit 36 is provided

and has the passage of motive fluid therethrough regulated by a two-way valve 37, the plug of which carries an operating handle 38. A branch conduit 39 communicates with one part of the valve 37 and with a cylinder 40 secured to one side of the cylinder 3. Within the cylinder 40 is movably arranged a spring balanced valve 41, the piston rod of which passes through a stuffing gland 42 and is connected to an arm 43, a coupling 44 being interposed in the piston rod of the valve and normally engaged by a pivotal catch or trip 45 mounted upon an adjacent arm formed on the cylinder 40 and secured to the cylinder 3. An exhaust opening 46 is formed in the bottom of the cylinder 40 while a discharge port 47 is formed in one side thereof and communicates with the port 4 formed in the cylinder 3. To another side of the marginal flange 7' is secured a bracket arm 48, which arm is in turn engaged with the arm 43. Due to the weight of sub-base 7, with its several parts attached and connected thereto, resting upon and thereby forcing down spring balanced valve 41, thus opening ports 47 and 4, allowing air or motive fluid from two-way valve 37 to pass into cylinder 3, which forces upward plunger 6, supporting sub-base 7 and work table 13, causing arm 43 attached to bracket arm 48 to engage with stop or regulating nuts on rod, working into cylinder 40 which releases trip 45 from a holding contact with coupling 44, thereby releasing spring-balanced valve 41, which when so released is forced upward, opening passage for exhaust of air from cylinder 3, through ports 4, 47, 46 which when so exhausted from cylinder 3, permits piston 6 to abruptly lower therein. The shock of the impact caused by the abruptly descending piston 6 and the sub-base 7 is absorbed by the buffer blocks 4' and as a consequence, material vibration, such as may harmfully effect the controlling and operation mechanism of the molding machine will be prevented.

To guide the sub-base 7, during its vibratory movement, depending arms 49 are secured to the under face of the same and are slidably received in the guide brackets 5.

In operation the molding flask and pattern are clamped on to the working table 13 and sand then placed in the same. Air is now admitted by way of the two-way valve 37 to the cylinder 40 and as a consequence, will cause the intermittent raising and lowering of the piston, sub-base and working table, that is, imparting a vibratory movement thereto, which vibratory movement serves to efficiently tamp the molding sand about the pattern arranged in the flask, thus, allowing a perfect impression or duplication to be obtained from the pattern. When the molding sand has been properly tamped in the flask, the two-way valve 37 is closed, the

sub-base assuming its lowermost position. At this time, the three-way valve 33 is opened admitting air to the cylinders 30 and causing the pistons therein to be moved forwardly, thereby rotating the pinions 28 and causing pivotal movement of the work table 13. Such pivotal movement of the work table will move the flask on to the work receiving table 18 which has been previously adjusted with relation thereto. When the flask is deposited on the work receiving table the piston 6 carrying the sub-base and working table is moved upwardly, thereby permitting the withdrawing pattern from finished mold. The work table is then returned to original position and air exhausted from cylinder 3, piston 6, with sub-base 7 and work table 13 dropped to lowermost position, while the pistons 29' are returned to normal positions in their respective cylinders 30 by reversing flow of air or motive fluid thereinto ready for the making of other molds.

Manifestly, the construction shown is capable of considerable modification, and such modification as is within the scope of our claims, we consider within the spirit of our invention.

We claim:

- 30 1. In a molding machine, a cylindrical base, a piston movable in said base and carrying a subbase, a table hinged to the subbase, and independently operable pneumatic control means for moving the piston and hinged table, certain of said pneumatic control means being connected to said sub-base and adapted to be intermittently actuated.
2. In a molding machine, a cylindrical base, a piston movable in said base and carrying a subbase, a table hinged to the subbase, intermittently operable pneumatic control means for causing vibratory movement of the piston and subbase, said control means being connected to the subbase and operated thereby, and other pneumatic control means for imparting movement to the hinged table.
3. In a molding machine, a cylindrical base, a piston movable in said base and carrying a subbase, a shaft mounted in bearings upon one side of said subbase, pinions mounted on the opposite extremities of said shaft, a table mounted on said shaft and movable therewith, pneumatically operated

racks meshing with said pinions, means for controlling the passage of air to the pneumatically operated racks, and other pneumatic control means for causing vibratory movement of the piston.

4. In a molding machine, a cylindrical base, a piston movable in said base and carrying a subbase, a shaft mounted in bearings to one side of the subbase, pinions keyed to the opposite ends of said shaft, a work table mounted on and movable with said shaft, pneumatically actuated racks meshing with said pinions, means for controlling the passage of air to the pneumatically actuated racks, other pneumatic control means for causing vibratory movement of the piston and subbase, and a vertically adjustable work receiving table secured to one side of said base.

5. In a molding machine, a cylindrical base, a piston movable in said base and carrying a subbase, a shaft mounted in bearings to one side of the subbase, pinions keyed to the opposite ends of said shaft, pneumatically actuated racks meshing with said pinions, means for controlling the passage of air to the pneumatically actuated racks, an adjustable work receiving table secured to one side of the base, and pneumatic control means operable upon movement of the subbase for causing vibratory movement of the same and said piston.

6. In a molding machine, a cylindrical base, a piston movable in said base and carrying a subbase, a shaft mounted in bearings to one side of the subbase, a table mounted on and movable with the shaft, pinions keyed to the opposite ends of the shaft, pneumatically actuated racks meshing with said pinions, pneumatic control means for regulating the passage of air to said pneumatically actuated racks, a vertically adjustable work receiving table secured to the base, and a spring balanced air controlling valve communicating with said cylinder and operable upon movement of the subbase for causing vibratory movement of the same and said piston.

In testimony whereof we affix our signatures hereto.

CHESTER H. STEELE.
FRANK H. SCATTERGOOD.
